Primary Examiner — Cathron C Brooks*Assistant Examiner* — Samantha Q Lawrence(74) *Attorney, Agent, or Firm* — Dickinson Wright PLLC(57) **CLAIM**

The ornamental design for a needle tip shield, as shown and described.

DESCRIPTION

FIG. 1 is a top front perspective view of a needle tip shield;
 FIG. 2 is a bottom perspective view thereof;
 FIG. 3 is a top rear perspective view thereof;
 FIG. 4 is a top view thereof;
 FIG. 5 is a side view thereof;
 FIG. 6 is an opposite side view thereof;
 FIG. 7 is a bottom view thereof;
 FIG. 8 is an enlarged view of a portion of FIG. 7, taken from
 FIG. 7;
 FIG. 9 is a front view thereof; and,
 FIG. 10 is a rear view thereof.

The broken lines shown in FIGS. 1-3 and FIGS. 6-8 illustrate portions of the needle tip shield that form no part of the claimed design.

1 Claim, 6 Drawing Sheets(56)
